UNITED STATES PATENT OFFICE.

VINCENT J. BURNELLI, OF NEW YORK, N. Y.

RETRACTILE FLOAT FOR FLYING BOATS.

Application filed December 31, 1927. Serial No. 243,871.

This invention relates to flying boats such as are provided with stabilizing floats pendant from wings and my improvements are directed to means for mounting a traction wheel 5 in each of the floats, for land service, together with means for adjusting said floats vertically, whereby the wheels may be lowered for land service and raised when the craft is in flight or floating on water.

10 Other features and advantages of my invention will hereinafter appear.

In the drawings:

Figure 1 is a partial side elevation of a flying boat showing my improved wheel carrying float, in hinged relation with a wing, for vertical adjustment.

15 Fig. 2 is a partial view in front elevation of the flying boat, having a side float carried by a wing, a portion of the wing being broken away to show the shock absorbing means and the means for communicating vertical movement to the float.

20 Fig. 3 is an enlarged sectional detail of the shock absorbing and vertical movement actuating means.

Fig. 4 is a front elevation of a flying boat equipped with my improvements, and

Fig. 5 is a side elevation thereof.

In said views let 1 indicate the hull or boat 20 of a flying boat, 2 the main supporting airfoil, 3, 3 side airfoils extended respectively from the opposite sides of the boat, and struts 4, 4^a connecting airfoils 2 and 3. While a bi-plane airfoil arrangement is given in the example of my invention herein illustrated it is to be understood that I am not limited to the bi-plane type of sustaining wings, as my improvement, to be hereinafter described in conjunction with the wings 3, 3, may equally well be employed with a flying boat having a monoplane airfoil. The floats 5, 5 which are each provided with bulkheads 6 to form water tight compartments 7, each have a recess 8 formed in the forward portion, open 45 at the bottom and adapted to partly enclose a wheel 9, only the lower portion of said wheel, below the hub, projecting below said float.

The wheel 9 is journaled in a frame composed of the fork members 10, the horizontal member 11 extended rearwardly therefrom against the under surface of the float top, and the angled members 12 that converge upwardly and rearwardly from the wheel hubs, 55 merging with the member 11 near the upper

rear end of the float, where the frame structure projects through the float top, there having pivotal engagement, at 13, with a vertical spar 14, that extends through an airfoil 3 and connects with a strut 4^a. It will 60 be noted that the nose portion 15 of the pontoon is of convex contour to reduce head resistance, while the lower, exposed portion of wheel 9, also presents a stream line effect adapted to minimize head resistance. 65

The float structure and contained wheel as shown in full lines in Fig. 1 represents the position of these elements when the flying boat is in flight or operating on water, but when the flying boat is required to land upon 70 or take off from a solid surface then the floats are to be lowered to the position thereof indicated in dot and dash lines in Fig. 1. The instrumentalities whereby this lowering operation (also the return) is effected are as 75 follows:

The upper ends of fork members 10 are provided with horizontal slots 16 with which pins 17 carried by a vertical shaft 18 are engaged, said shaft being threaded 80 and passing freely through a rectangular frame 19 that contains a spool 20 and elastic elements 21 that constitute shock absorbing means. The spool 20 is threaded to engage the screw upon shaft 18, but is itself 85 prevented from moving vertically by being held between the lower portion of frame 19 and the elastic elements 21; consequently, as the spool 20 is rotated by means of a cable 22 that is wound thereon, thereby the shaft 18 is 90 given vertical movement. The cable 22 is passed to suitable operating means (not shown) under the control of the pilot. Obviously, by turning the spool in one direction shaft 18 will be moved downwardly, 95 carrying with it the float and the wheel journaled therein. Since the shafts 18 for both floats will be operated simultaneously thereby both wheels will be moved together into their lowered position for traction purposes. 100 Similarly, by reverse motions of the spools the floats and wheels will be retracted.

The floats 5, in their vertical movements, swing upon the axes provided by their hinge joints 13, and the slots 16 provide the requisite 105 play for pins 17 in the arcuate path that is followed by the floats in those movements.

The frames 19 enclosing the spools and shock absorbers are each contained within the leading edges of an airfoil 3, which if 110

necessary, may be provided with a localized enlargement, as at 23, for such enclosing means.

It will be observed that whereas the spars 5 14, to which the floats are hinged, connect with the rear struts 4^a, the shafts 18, which support the floats at their forward portions, and which communicate vertical movement thereto, are extended up between the forward 10 struts 4.

Variations within the spirit and scope of my invention are equally comprehended by the foregoing disclosure.

I claim:

15 1. The combination with a flying boat having an airfoil, of a float in hinged relation at its rear portion to said airfoil, said float carrying a traction wheel, and vertically movable engaging means between said float at its

forward portion and said airfoil, whereby 20 said float may be swung into lowered and retracted positions.

2. The combination with a flying boat having an airfoil, of a float in hinged relation at its rear portion to said airfoil, and means enclosed in the leading edge of said airfoil to move said float into extended and retracted 25 positions.

3. The combination with a flying boat having an airfoil, of a float in hinged relation at its rear portion to said airfoil, means enclosed in the leading edge of said airfoil to move said float into extended and retracted 30 positions, and shock absorbing means also enclosed in said leading edge.

New York, December 28th, 1927.

VINCENT J. BURNELLI.
